2 Sheets-Sheet 2

UNITED STATES PATENT OFFICE.

HARRY M. PFLAGER, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE STRUCTURE.

Application filed July 14, 1926. Serial No. 122,375.

My invention relates to railway rolling stock and consists in an improved locomotive rear end structure. In recent years, the size of the locomotives has been increased substantially, and particularly the locomotive fire box and ash pan have increased to take care of larger boiler requirements and to effectively burn lignite and inferior grades of coal. The supporting of these large fire boxes has been a problem, the solution of which has resulted in departures from the well known locomotive construction in which the fire box and adjacent superstructure has been mounted upon a cradle secured to the rear end of the main frame of the locomotive and partially supported upon trailer wheels either journaled in the cradle or forming part of a trailer truck pivoted to the locomotive main frame. One solution of the problem is embodied in the structure shown in my copending application Serial Number 124,662, filed July 24, 1926, in which the cradle is widened so that its sides are located outside of the truck frame, thereby providing more room for the fire box and ash pan.

Another arrangement is shown in Thomson Patent No. 1,145,524, in which a central cradle-like member is provided at the rear of the main frame of the locomotive and is supported at a single point upon a pony truck having a center plate connection to the cradle.

The main object of my present invention is to utilize some of the features shown in the different arrangements referred to in combination with other features whereby adequate superstructure support is provided with a maximum amount of space for large fire box and ash pan members and whereby the longitudinal stresses may be properly taken care of by a cradle member forming an extension of the locomotive bed.

An additional object of my invention is to provide a cradle member which extends centrally of the locomotive but which is supported at points spaced substantially from the locomotive center line and is also adapted to support the locomotive superstructure at similarly spaced points.

Another object of my invention is to provide a cradle member of the type referred to in a one-piece casting, thereby securing the maximum amount of strength for a given

amount of metal and eliminating the necessity for providing for assembly of a number of parts such as is required in the built-up structure. 55

Preferably, I form the centrally located cradle member integrally with the locomotive main frame or bed and the provision of such structure is an additional object of my invention. 60

In the accompanying drawings which illustrate my invention— 65

Figure 1 is a one-half longitudinal top view of the locomotive cradle member and adjacent portion of the main frame or bed and the trailer truck with which these parts are assembled. 70

Figure 2 is a transverse section taken substantially on line 2—2 of Figure 1.

Figure 3 is a side elevation of the same parts with the locomotive mud ring and ash pan also shown. 75

Figure 4 is a view similar to Figure 1 but showing the cradle portion alone and modified somewhat from its preferred structure.

Figure 5 is a section similar to Figure 2 but illustrating a modified ash pan arrangement. 80

The rear end of one of the side members 1 of the main frame is shown in its relation to the rear driver 2 and extending rearwardly therefrom is the centrally located cradle member 3, here shown as being box-shaped in cross section through substantially all of its length and having each of its sides diverging at its forward end to merge with the rear end of the adjacent side frame 1. Preferably the main frame and cradle are integrally formed in a one-piece casting. 85

The rear end of the cradle member is shaped to provide an integral foot plate 4 and the drawbar pocket forming elements 5. The rear portion of the cradle is also provided with integral transversely extending arms 6 which are supported upon suitable rocker bearings 7 carried by the trailer truck frame 8, the sides or wheel pieces of which are spaced apart a greater distance than the main frame sides 1. 95

The outer portions of arm 6 form brackets 9 for expansion plates 10 which support the rear end of the mud ring 11. Preferably the ash pan 12 is mounted upon the trailing truck frame 8, see Figure 2, although this mounting of the ash pan is not essential. 100

and the ash pan may be carried by the mud ring as is familiar practice. I prefer that the ash pan extend over the cradle member 3 and be spaced therefrom so as to protect 5 the cradle member from the hot ashes.

In the modification shown in Figure 5 I illustrate an arrangement of the ash pan 26 and truck frame 27 in which the ash pan hoppers 28 extend over the truck frame. 10 This construction does not materially affect the construction of the cradle member 29.

The forward portion of the cradle has transverse arms 13 which project outside of the face of the main frames 1 and are provided with suitable brackets 14 which carry the front end of the mud ring. The outer end of each arm 13 is provided with an integral brake hanger bracket 15 adjacent to the rear driver 1.

20 A preferred form of trailer truck comprises a four wheel truck having a frame, the sides of which converge in front of the truck to form a central pivotal connection to the front end of the cradle structure, as indicated at 16. The rear of the trailer truck is adapted to carry a booster motor 17 which may be operatively connected to the truck axle to assist the main cylinders and drivers in starting the locomotive under a heavy 25 load or in propelling the locomotive up a steep grade.

The weight of the cradle and its load is preferably distributed to the trailer truck and the driving axles through an equalized 35 spring system including equalizers 18 and 19 pivoted on the truck frame and links 20 which support the end of the equalizers from the ends of the springs 21, this being a well-known and satisfactory equalizing system.

40 In the modification illustrated in Figure 4, the cradle member is shown as being formed complete, but separate from the locomotive main frame and adapted to be attached thereto by bolts or other securing means. In 45 this embodiment of my invention the main portion 22 of the cradle is of I-shape cross section but the forward end is bifurcated to provide spaced walls 25 for attachment to the main frame of the locomotive. The 50 main features of my preferred construction are retained including the transverse arms 23 to be supported on the truck side bearings and for carrying the rear end of the fire box structure. This form also preferably 55 includes the arms 24 corresponding to the arms 13 of the cradle shown in Figures 1 and 3.

Obviously these or similar cradle members may be mounted upon two-wheel trailing 60 trucks as well as four-wheel trailing trucks and the cross sectional shapes and disposition of ribs and surfaces may be changed as desired. These and other modifications in the 65 details of my invention may be made without departing from the spirit thereof, and I

contemplate the exclusive use of such modifications as fall within the scope of my claims.

I claim:

1. A one-piece cast locomotive frame comprising a front portion having longitudinal side members, and a central portion extending rearwardly of said members. 70

2. A one-piece cast locomotive frame comprising a front portion having spaced sides, and a centrally located portion of box cross section extending rearwardly of said frame. 75

3. A one-piece locomotive frame comprising a front portion having spaced sides, and a centrally located portion extending rearwardly of said sides and having laterally extending members for supporting the locomotive superstructure. 80

4. A one-piece locomotive frame comprising a front portion having spaced sides, and a centrally located portion extending rearwardly of said sides, there being transverse members on said central portion extending beyond the planes of said sides and adapted to support locomotive superstructure near 90 their outer ends. 85

5. A one-piece locomotive frame comprising a front portion having spaced sides, and a centrally located portion extending rearwardly of said sides, there being transverse members on the front and rear ends of said central portion extending beyond the planes of said sides and adapted to support locomotive superstructure. 95

6. In a locomotive cradle, a central longitudinal member adapted to extend under the fire box of the locomotive and to transmit longitudinal stresses, and lateral projections on said member for supporting the fire box adjacent the sides of the same. 100

7. In a locomotive cradle, a central longitudinal member adapted to extend under the fire box of the locomotive and to transmit longitudinal stresses, and transversely spaced bearings on said member for supporting the same on a trailer truck frame outside of the wheel tread. 110

8. A locomotive cradle member comprising a one-piece casting box-shape in cross-section and adapted to extend under the central portion of the fire box and to transmit longitudinal stresses between the locomotive main frame and rolling stock behind the locomotive. 115

9. A locomotive cradle member comprising a one-piece centrally located draft-transmitting element having an integral foot plate formed on its rear end. 120

10. A locomotive cradle member comprising a one-piece centrally located draft-transmitting element having an integral foot plate and an integral drawbar pocket formed on its rear end. 125

11. In a locomotive, a main frame, a radial trailer truck, and a central draft-transmit- 120

ting member extending from said main frame over said truck and supported on the latter.

12. In a locomotive, a main frame, a radial 5 trailer truck, and a central draft-transmitting member extending from said main frame over said truck and supported on the latter, and an ash pan carried on said truck.

13. In a locomotive, a main frame, a radial 10 truck including a frame, side bearing carrying elements on said frame, and a central draft-transmitting member extending from said main frame over said truck and supported on said side bearings.

14. In a locomotive, a main frame, a radial truck including a frame, side bearing carrying elements on said frame spaced a greater distance from each other than the sides of said main frame, an ash pan carried on said 20 frame, and a central draft-transmitting member extending from said main frame over said truck and ash pan and supported on said frame.

15. In a locomotive, a main frame, a radial 25 truck, and a central draft-transmitting mem-

ber extending from said main frame over said truck and supported thereon near its rear end and having transverse arms at its front and rear ends for supporting the locomotive fire box.

16. In a locomotive, a main frame, a radial truck, and a central draft-transmitting member extending from said main frame over said truck and having transverse arms at its front and rear ends for transferring its 30 weight and load to the rear portions of said truck and main frame.

17. In a locomotive, a main frame, a radial truck, and a central draft-transmitting member extending from said main frame over 40 said truck and having transverse arms at its front and rear ends for transferring its weight and load to the rear portions of said truck and main frame, and for supporting the front and rear portions of the locomotive 45 fire box.

In testimony whereof I hereunto affix my signature this 10th day of July, 1926.

H. M. PFLAGER.
